(57) **CLAIM**

The ornamental design for a chair, as shown and described.

DESCRIPTION

FIG. 1 is a front, perspective view of a chair, showing my new design;

FIG. 2 is a rear perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof; and,

FIG. 8 is an enlarged detailed view of boxed area 8 in FIG. 2.

The evenly dashed broken lines illustrate portions of the chair which form no part of the claimed design. The dot-dash broken lines illustrate the border of the enlarged detailed view and form no part of the claimed design.

1 Claim, 8 Drawing Sheets
